UNITED STATES PATENT OFFICE.

ERNEST D. ANDERSON, OF NEW YORK, N. Y., ASSIGNOR TO E. D. ANDERSON, INC., OF NEW YORK, N. Y., A CORPORATION OF NEW YORK.

CARTONING-MACHINE.

1,359,946.

Specification of Letters Patent. Patented Nov. 23, 1920.

Application filed May 19, 1917. Serial No. 169,678.

To all whom it may concern:

Be it known that I, ERNEST D. ANDERSON, a citizen of the United States, and resident of New York city, borough of Manhattan, 5 in the county of New York and State of New York, have invented certain new and useful Improvements in Cartoning-Machines, of which the following is a specification.

10 My invention relates to improvements in means for automatically charging articles or goods into receptacles or cartons successively, and has for its object to provide novel means for conveying receptacles or 15 cartons to be charged with the required contents and discharging them from the machine.

My invention also comprises novel details of improvement and combinations of parts 20 that will be more fully hereinafter set forth and then pointed out in the claims.

Reference is to be had to the accompanying drawings forming part hereof, wherein,

Figure 1 is a front elevation of a machine 25 embodying my invention; Figs. 1^a and 1^b are respectively detail side and plan views of a portion of a conveyer for the receptacles or cartons to be opened, charged and closed; Fig. 2 is a plan view, parts being 30 removed; Fig. 3 is a detail perspective view illustrating a portion of the conveyer and the opener for the receptacles; Fig. 4 is a detail side view, partly in section, of a portion of the conveyer, illustrating a receptacle opened therein; Fig. 5 is an enlarged detail sectional view illustrating feeding 35 means for collapsed receptacles or cartons, the figure being taken substantially on the line 5—5 in Fig. 2; Fig. 6 is a plan view of 40 Fig. 5.

Similar numerals of reference indicate corresponding parts in the several views.

The main frame of the machine may be constructed in any suitable manner. It is 45 shown comprising a table or plate 1 mounted upon standard or upright 2. Since it is desirable in some machines to feed collapsed receptacles or cartons successively into position to be opened and charged with 50 articles, I have illustrated an endless conveyer 3, shown substantially in the form of a chain supported upon spaced plain idler wheels 4, 5, journaled in bearings upon the main frame, a lower bight of the conveyer 55 passing under a driving sprocket wheel 6,

that is secured upon a shaft 7 journaled upon standard 2, (Fig. 1). Any suitable means may be provided for operating said conveyer step by step. I have shown a drive shaft 8 that is journaled upon standard 2 and provided with a pinion 9 in mesh with a gear 10 secured upon a shaft 11 journaled upon standard 2. Said shaft may be provided with an arm 12 of a Geneva movement, the projection or roller 13 of which 60 arm is adapted to coöperate with the slotted portions of the wheel or member 14 of said movement which is secured upon shaft 7, whereby as shaft 7 is rotated step by step by said gearing and Geneva movement, the 65 conveyer 3 will be correspondingly operated. Said conveyer is shown provided with correspondingly spaced receivers or pockets 15 to receive receptacles or cartons 16. In the example illustrated the receivers 70 or the pockets 15 are provided between adjustable walls or the like 15^a spaced apart upon the respective blocks 3^a of the conveyer, adapted to receive collapsed receptacles or cartons 16 to be opened in said receivers. In the form of conveyer illustrated the blocks 3^a of the conveyer are 75 channel-like on their inner sides and have holes in their side webs receiving pins or rods 3^b on which links 3^c are journaled at 80 opposite ends of the blocks for connecting them together in the manner of a chain. The channels in the blocks receive and are 85 guided by the wheels 4, 5 and 6. The receptacles 16 rest in the pockets 15 and the 90 walls 15^a are shown slotted at 15^b to receive screws 15^c that enter the blocks, (Figs. 1^b and 4) whereby said walls may be adjusted and held by said screws, said wall being in 95 front and back of the articles or receptacles carried on the conveyer. The arrangement is such that the chain lengths may be divisible by the number of slots or stop teeth of the Geneva movement so that the same block 3^a will always coact with the same Geneva 100 stop to assure the presentation of the receptacle 16 on the corresponding block always in proper position to receive the opener and charges of articles hereinafter referred to. By so arranging the blocks 3^a 105 with respect to the slots or stop teeth of the Geneva movement, correct registry of the pockets carrying the receptacles with respect to receptacle opening and charging devices is made possible with a more or less loose 110

construction incident to the use of a chain form of conveyer. The wear on a block will always correspond to a given portion of the drive wheel. Furthermore, the position 5 of the pockets on the chains can always be adjusted to a given step of the Geneva movement for assurance that such pocket will always register even in case of wear. The adjustability of the walls 15^a on the 10 conveyer blocks enables the positioning of the receptacles on the blocks in proper relation to the corresponding Geneva stop and to the opener and charging devices. I have shown a suitable magazine 17 for retaining 15 receptacles 16 in stacked relation. Said magazine may be supported upon the main frame in any suitable manner to permit delivery successively of the lowermost receptacle or carton through the customary opening 20 at the lower delivery corner of the magazine. The magazine is shown supported upon a plate 18 that is supported above table 1 of the main frame by uprights 1^a (Fig. 1). The delivery end of plate 18 25 is above the receivers of the conveyer, and upon plate 18 is a pusher 19 guided by guides 20 to reciprocate upon plate 18 to successively push receptacles or cartons 16 from the bottom of the magazine. The 30 pusher 19 is adapted to enter the magazine through a bottom space or opening 17^b thereof (Fig. 6). Any suitable means may be provided to reciprocate pusher 19. I have shown a link 21 pivotally connected 35 with said pusher at 22 and pivotally connected with a rock arm 23 secured upon a shaft 24 journaled in a support 25 carried by table 1. A crank arm 26 secured to shaft 24 is adapted to be rocked by a rod 40 27 pivotally connected with a crank arm 28 on a shaft 29 (Fig. 1), journaled in bearings in standard 2. Rod 27 is shown provided with a universal joint at 30 (Figs 1 and 5) to accommodate different angular 45 movements of said rod as it is operated by crank 28, such joint being shown attached to arm 26. Shaft 29 may be rocked for communicating rocking motion through rod 27 from crank arm 28 to crank arm 26. I 50 have shown said shaft provided with a projection 31 connected to a reciprocative bar 33, the lower end of which is forked to straddle and be guided by shaft 11, which bar is provided with a projection or roller operated by 55 a suitable cam driven by shaft 11. The arrangement so far described is such that as shaft 8 is rotated by any suitable prime mover, the conveyer 3 will be moved step by step to bring its receivers successively to 60 rest at one side of the delivery edge of plate 18, and pusher 19 will be reciprocated, in timed relation to the movements of the conveyer, to push the receptacles 16 successively from the bottom of the magazine 17 65 to cause their deposit in the successive receivers

receivers 15 of the conveyer, substantially as indicated in Fig. 5. The collapsed receptacles or cartons 16 drop into the conveyer receivers between spaced guides or abutments 36, which extend a suitable distance 70 in the direction of travel of the receptacles, to limit endwise movement of the latter in the receivers of the conveyer. At 37 is an abutment or stop (Figs. 1, 2, 5 and 6) shown pivotally supported at 38 between spaced 75 arms 39 that are pivotally supported at 40 (Figs. 1 and 2). The arms 39 are normally above the line of travel of the receptacles within the conveyer to keep the receptacles from rising. The abutment or stop 37 is 80 normally resisted by a spring 41 carried by an arm 39, and the lower end of said stop is shown provided with a hooked portion at 37^a in position to be engaged by the upper forward edges of the receptacles 16, as 85 they are carried along by the conveyer, to cause the receptacles to be snugged in the respective receivers of the conveyer. The arms 39 may be raised to lift the stop 37 out of the path of the receptacles, and to 90 permit access to receptacles on the conveyer, whenever desired. A screw at 42 operative in a support *a* on table 1 is adapted to work in a threaded projection 39^a on an arm 39 to retain arms 39 in closed position over 95 the conveyer (Figs. 1, 2 and 6).

When a receptacle has engaged stop 37 and thereby has been snugged in the receiver 15 of conveyer 3, the conveyer will be brought to rest and the collapsed receptacle 100 will be opened. I have shown an opener 43 in the shape of a suitable blade located in position to enter the successive receptacles as they are brought to rest (Figs. 2, 3, 4, and 6). In the example illustrated, said 105 opener is adapted to enter the receptacles 16 through opening 36^b in the opposing guide or abutment 36 (Fig. 5). As the conveyer passes from wheel 4 it is shown adapted to rest upon a guide or way 44, suitably supported upon table 1, whereby the conveyer will be supported and guided for various operations upon the receptacles or cartons thereon, and whereby the receptacles will be retained in proper position on the conveyer 110 when the opener 43 operates to open said receptacles, and when other operations are performed. Any suitable or well known means may be provided to reciprocate and rotate the opener 43. The position of a receptacle 115 16 opened in a receiver of the conveyer is shown in Fig. 4. When the conveyer next steps forward the said opened receptacle will be advanced, and another succeeding collapsed receptacle will be brought by the conveyer in position opposite the opener to be 120 opened by it and seated in the corresponding receiver of the conveyer, in manner previously stated.

When an opened receptacle has been 130

brought to rest on the conveyer, it may be charged with one or more articles according to the character of the goods to be packed.

When the charged, closed and sealed receptacles 16 have been brought to position opposite the receiving end of guideway 136, they are successively delivered thereon from the conveyer.

My improvements embody simple and direct acting mechanism, timed to operate in proper order, and the conveyer is supported and operated in a simple and accurate manner, the construction of the conveyer having the adjustable walls thereon providing simple means to enable the articles or receptacles to be positioned upon the conveyer accurately with respect to opening and other devices.

Changes may be made in the details of construction and arrangements of parts set forth, as the same may be varied, within the scope of the appended claims, without departing from the spirit of the invention.

Having now described my invention what I claim is:—

1. A conveyer comprising a plurality of blocks movably connected together, each of said blocks having spaced walls mounted thereon in front and back of the articles carried providing receivers for articles therebetween, and means to adjustably secure said walls to the blocks to regulate the positions of the receivers thereon.

2. A conveyer comprising a plurality of blocks movably connected together, each of said blocks having spaced walls mounted

thereon in front and back of the articles carried providing receivers for articles therebetween, said walls having slots, and screws in said slots threaded in the blocks to permit adjustment of said walls with relation to the blocks to regulate the positions of the receivers on the blocks.

3. A conveyer comprising a plurality of blocks having channels on their inner sides and provided with receivers upon the opposite sides having adjustable walls in front and back of the articles to be carried, links movably connecting the blocks together with said channels opposing, plain faced idler wheels for the conveyer adapted to enter the channels of said blocks, and means to propel the conveyer.

4. A conveyer comprising a plurality of blocks having channels on their inner sides and provided with receivers upon the opposite sides having adjustable walls in front and back of the articles to be carried, links movably connecting the blocks together with their channels opposing, plain faced idler wheels for the conveyer adapted to enter the channels of said blocks, a sprocket wheel coöperative with said blocks for operating the conveyer, and means to rotate said sprocket wheel.

Signed at New York city, in the county of New York and State of New York this 16th day of May, A. D. 1917.

ERNEST D. ANDERSON.
